(57) **CLAIM**

The ornamental design for a jar packaging, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1.1—Front view of the first embodiment;

FIG. 1.2—Rear view of the first embodiment;

FIG. 2.1—Front view of the second embodiment;

FIG. 2.2—Rear view of the second embodiment;

FIG. 3.1—Front view of the third embodiment; and

FIG. 3.2—Rear view of the third embodiment.

**1 Claim, 6 Drawing Sheets
